US00D582847S

(12) **United States Design Patent**
Wang

(10) **Patent No.:** **US D582,847 S**
(45) **Date of Patent:** **** Dec. 16, 2008**

(54) **ELECTROMAGNETIC STARTER SWITCH**

(75) Inventor: **Weibin Wang, Yueqing (CN)**

(73) Assignee: **Chint Group Corp., Zhejiang Province (CN)**

(**) Term: **14 Years**

(21) Appl. No.: **29/272,670**

(22) Filed: **Feb. 15, 2007**

(30) **Foreign Application Priority Data**

Nov. 10, 2006 (CN) 2006 3 0156920

(51) **LOC (8) Cl.** **13-01**

(52) **U.S. Cl.** **D13/113**

(58) **Field of Classification Search** ..... D13/112–113, D13/118, 122, 123, 133, 184, 199; D15/1–5; 335/16, 27, 38; 290/47–48, 38 R; 310/46, 310/68 R, 48, 89, 109; 123/185.14, 185.1, 123/179.28, 179.1; 74/78

See application file for complete search history.

(57) **CLAIM**

The ornamental design for the electromagnetic starter switch, as shown and described.

DESCRIPTION

FIG. 1 is a front perspective view of the electromagnetic starter switch showing my new design;

FIG. 2 is a front elevational view thereof;

FIG. 3 is a rear elevational view thereof;

FIG. 4 is a bottom plan view thereof;

FIG. 5 is a top plan view thereof;

FIG. 6 is a right side elevational view thereof; and,

FIG. 7 is a left side elevational view thereof.

1 Claim, 7 Drawing Sheets

FIG. 1

FIG. 2

FIG. 3

FIG. 4

FIG. 5

FIG. 6

FIG. 7
